MACHINE FOR SLICING MEATS

Karl Eric Olsson, Stockholm, Sweden

Application September 13, 1933, Serial No. 689,187

10 Claims. (Cl. 146—103)

The present invention relates to new and improved devices in meat slicing machines of the kind provided with a knife rotatably journaled on a swingable arm or holder, and a table for the material to be sliced, the said table being movable perpendicularly to the knife path, the arm carrying the knife being mounted in one end or corner of the frame of the machine below the horizontal plane of the table, so that, when 5 swinging the arm from the resting position to the slicing position, the knife will have a very short distance to move and the work is facilitated.

The general object of the invention is to obtain a simple and cheap construction.

15 A particular object of the invention is to provide an effective knife guard for the knife-edge under the abovementioned conditions. This arrangement eliminates the risks of accidents, when operating the machine, the risks in the said 20 devices being considerably greater than, for instance, in machines having stationary knives.

A further object is to provide in a machine having the knife arm placed and movable in the frame of the machine in the manner indicated; 25 a device by means of which the knife is caused to rotate only when the arm is being swung downward (from the resting position to the slicing position).

Further characteristics of the invention include simplified and effective means for automatically feeding the table adapted to carry the meat toward the path of the knife under positive control of the movements of the knife arm. It may be stated in this connection that the invention also includes means for blocking the motion of the table in the opposite direction, and for releasing the blocking device when necessary.

The said and other characteristics are illustrated in the accompanying drawings, in which

Fig. 1 is a front view of the machine with the knife shown partly in a raised position, and partly in dot and dash lines in a swung down intermediate position;

Fig. 2 is a top view of the front end of the machine;

Fig. 3 is a top view of the whole machine, certain parts being cut away;

Fig. 4 is a side view, partly in section of the 50 shaft construction by which the slicing table is actuated;

Fig. 5 illustrates details of the said construction viewed from above;

Fig. 6 is a section along the line VI—VI of 55 Fig. 3,

Figs. 6A, 6B are sectional detail views, taken on the line A—A of Figure 6, and show one of the table guide means. In Figure 6A, the table is in advanced position, and in Figure 6B, the table is in returned position and guide bar 22 has 5 been given a one quarter rotation by the handle H.

Fig. 7 is a detail on a larger scale of a drive and stop mechanism for the above mentioned shaft constructions partly in section and with 10 certain parts cut away,

Fig. 8 is a front view of the coupling device for rotating the knife, certain parts being removed;

Fig. 9 is a similar front view, a cover for the 15 coupling being removed,

Fig. 10 is a top view of the same device, the cover surrounding the same being cut away,

Fig. 11 is a section along the line XI—XI of 20 Fig. 9 and

Fig. 12 is similar to Fig. 10, but includes added detail.

In all the figures equivalent parts are indicated by the same reference numerals.

The main parts of the machine consist of a 25 circular knife 2 rotatably journaled on a handle-provided holder or arm 4 which is swingably mounted in a vertical plane in the frame 3, and of a table 5 movable in the frame toward and from the knife and thus perpendicularly to the 30 knife path. Table 5 is provided, in a way known per se, with clamping devices for the material to be sliced, the said clamping devices having an adjustable clamp 6 in the shape of a stirrup and fixing pins 68, 69 on the table and the stirrup respectively, the said stirrup being provided with a setting screw 61 having an adjusting handle. Moreover the table is provided with a guide and cutting edge 7. The table is gradually advanced toward the knife path by means of a 40 feeding mechanism the movement of which is controlled by movement of the arm 4 and which will be more particularly described below. 8 indicates a plate or the like for receiving the sliced meat, and 9 indicates a detachable bottom mem- 45 ber.

The operating arm 4 is secured to a shaft 10 which is pivotally mounted in the rear part of the frame inside the longitudinal side of the frame and below the table 5. By this arrangement a very short movement of the knife from the upper position (the resting position) to the slicing position is obtained, and thus the work is facilitated.

As, however, during this movement the knife- 55

edge may be easily subjected to damage, and because due to the said position of the swinging shaft there are many more risks of accidents when manipulating this type of machine than in machines having the knife mounted in another way, a knife guard is provided. This guard is carried by the machine-frame or made in one piece with the machine-frame, and consists of a frame, flange or rib 11, which from 10 the rear edge of the machine-frame first runs rearward and then in a curve upward and forward toward the front machine-frame edge. The curve is first approximately circular but then shaped in accordance with the envelope curve 15 of the knife-edge, and thus the knife is protected from above during its motion and may in the raised (resting) position be sufficiently drawn back within the outline of the knife guard to leave a free working space for placing meat in 20 position upon, or removing meat from the table. The flange 11 is connected with a plate 12, which completely protects the knife from the inside (the table side). From the arm 4 extends a 25 bar or guard arm 13 in a curve along part of the periphery of the knife, which bar with its upper edge extends a little over the knife-edge and is axially displaced a little outward relatively to the knife-edge (from the middle of the table). When the arm is swung down to the slicing position 30 the bar avoids injury from (involuntary) grasping of the front edge of the flange 11. Of course the protection bar must be so made as to not extend over the part of the knife-edge curve (about $\frac{1}{4}$ of the curve) necessary for effecting 35 the slicing.

If desired, a similarly shaped bar may run from the arm 4 in the opposite direction so that the risk of accidents from grasping the machine between the knife and the guard plate 12 may 40 be prevented when the knife is being swung upward from the swung-down position. The bars may also run peripherically in the radial plane of the knife a little outside the knife-edge and, if desired, be provided with a part swung out 45 (viewed from the table) like a curve which projects radially inward past the knife-edge. Shoulders 14, 14 limit the movements of the arm 4, and locking members 15, 16 are provided for locking the shoulders in the resting position and 50 in an intermediate position for grinding, respectively.

At the guard curve 11 is fixed a band 17 such as, a wire or rope of steel or any other suitable material. As shown in Fig. 12, the band is wound 55 on a roll 18 on a shaft 71 journaled in a casing 19 located on the arm 4 in which casing also the knife shaft 20 is journaled. On the shaft 20 is wedged a gear 72 which is held in its position by a stop nut 80 screwed on the threaded end of 60 the shaft. Gear 72 engages another gear 73, the latter being loosely journaled on the shaft 71. The said parts are situated in a widened portion of the casing 19. A plate 74 is fixed on the shaft 71 and is provided with tracks 75 for rolls 76 65 adapted to be actuated by springs 77 pressing the rolls to engage between the plate 74 and the gear 73. A spiral spring 78 is also provided and has one end fixed in the casing and its other end secured to the shaft 71.

70 When thus the arm 4 is swung downward the shaft 71 and also the plate 74 are rotated by the band 17 in the direction of the arrow so that the roll ratchet will carry along the gear 73 whereby the knife shaft is brought into rotation. The 75 spring 78 is, at this time, strained so that as

the arm is being returned the spring rotates the shaft 71 in the opposite direction whereby the band 17 is wound on the roll 18. The roll ratchet is during the last mentioned movement inoperative and thus the toothed rim and the shaft 5 20 remain idle. A detachable cover 81 covers the outside of the casing, and in the same is made a hole for the end of the shaft 20. This end of the shaft is provided with a bore 79 and a slot 82, adapted to receive a suitable key or 10 crank for manual operation of the knife shaft when, for instance, the knife is to be ground.

The table 5 travels by means of guides 21 or the like located on the underside on guide bars 22 pivotally journalled in the machine-frame. 15 The guide bars have flattened edges 22' on their rear portion of a length corresponding to the length of the guides and the bars can be turned by means of a handle H provided for each bar. By this arrangement the table in its completely 20 returned position is adapted to be removed from the bars. A rack 23 engages a toothed wheel 24, which, preferably by means of a screw 24' or the like, is detachably secured on a transverse shaft 25 pivotally mounted in the machine-frame. 25 A step feeding mechanism actuated by the shaft 10 of the knife arm 4 is adapted to effect a certain definite anticlockwise rotation of shaft 25 for advancing the table toward the knife. A suitable stop ring 25' serves to hold shaft 25 in position 30 in its bearing.

On the shaft 10 is provided a coupling member 26 which only on the rotation of the shaft in one direction (when the arm is swung upward) actuates a shoulder on a second coupling member 27 turnable on the shaft. From coupling member 27 extends an arm 28 provided with a shoulder or pin 29 engaging a shoulder or a pin 30 on one arm 31 of a two-armed lever pivotally mounted on the transverse shaft 25. 40 On arm 31 there is secured a spring 32 which tends to keep the members 29 and 30 in effective engagement with each other. The second arm 33 of the lever is provided with a widened head 34 for a roll ratchet for the wheel 35 secured 45 on the shaft 25. The track or guide path 36 for the roll 37, actuated from below by a spring 70, tapers upward so that, when moving the ratchet head downward, the ratchet carries along the wheel in the direction of the arrow, but, when 50 moving the ratchet head upward, releases the same and prevents rotation of wheel 35 in the opposite direction. A tension spring 38 is attached at its one end to the frame 83 of the machine and at its other end to lever arm 33 55 and tends to move the lever arm upward. A similar ratchet head 39 with roll 40 and track 41 for the roll is rigidly located in the frame; the ratchet allows the wheel to be turned in the direction of the arrow, but blocks it in the opposite direction. Several such ratchets may, of course, be provided, the said ratchets being actuated in the manner indicated below.

In the arm 33 and in a shoulder 42 extending upward from the ratchet head 39 are pivotally 65 mounted two-armed levers 43, 44 and 45, 46 respectively. The outer arms 44 and 46 each carry a tongue-like member extending from above and from below respectively into the respective ratchet track 36, 41 so as to rest against the rolls 37 70 and 40. The inner arms 43 and 45 are at their ends each provided with a shoulder or pin 47 and 48 respectively, which from above and from below respectively rest against the shaft 25 and the outer conical end of a sleeve 49 slidably mounted 75

on the shaft. A spring 50 presses the arm 45 upward.

In the shaft 25, the largest part of which is hollow, is mounted a second shaft or rod 51 which is operated from the outside by means of a handle 52 and which has a pin 53 projecting upward into an inclined groove 54 in the shaft 25. At its distal end the inner shaft 51 is also, by means of a pin 55 or the like engaging a groove, connected to and cooperating with the shaft 25, which pin also engages the sleeve 49 so that the sleeve is carried along by the movements of the respective shafts. For the pin there is in the outer shaft 25 made an oval hole 56 with the largest dimension in the axial direction, and the hole is further so arranged that the pin 55 receives as long a helical displacement as the pin 53 obtains at the turning of the shaft 51 relatively to the shaft 25.

Thus, if the shaft 51 is turned clockwise by means of the handle 52, the shaft receives, to begin with, a simultaneous peripheral and axial movement in the shaft 25 due to the groove and pin connection, whereby the sleeve 49 is displaced toward the wheel 35 so that the pins 47 and 48 run up on the conical end of the sleeve. Levers 43, 44, and 45, 46 thus receive an oscillatory motion by which the rolls 37 and 40 by the outer arms of the levers receive a displacement from the blocked position in the tracks to make it possible to turn the wheel clockwise. At a continued turning of the shaft 51 the said shaft can thus bring along the shaft 25 and thereby cause a backward motion of the table 5, if necessary. A spring 57 is located between the toothed wheel 24 and the sleeve 49, the said spring receiving a suitable strain by turning the wheel 24 to the necessary extent before the wheel is screwed on to the shaft. After releasing the handle 52 the spring 57 immediately returns the sleeve 49 and thus the shaft 51 to the position shown in Fig. 4, whereby the wheel 35 is blocked again against rotation clockwise. By means of the handle 52, however, rotation in the anticlockwise direction may freely take place, while the shaft 51 carries along the shaft 25 which is blocked.

In order to control the extent of the stepwise displacement and the length of the stroke respectively of the table 5 for the purpose of obtaining the desired thickness of the slices cut, there is on the outside of the machine-frame provided a graduated, turnable adjustment scale 58 with a handle 59, which scale is connected with a shaft or rod 60 pivotally mounted in the machine-frame. On rod 60 there is secured a sector plate 61 or the like against which a shoulder 62 or the like on the lever-arm 33, at the upward swing of the latter, will rest. According to the position assumed by the plate 61 the lever may thus receive a greater or smaller swinging motion and so control the step movements of the table. Other arrangements for the same purpose are, of course, possible.

On the shaft 60 there is moreover turnably, but non-removably mounted a sleeve or body 63 provided with an upward directed pin 64 or the like cooperating with a pin or shoulder 65 on the underside of the table 5 for limiting the displacement of the table. A horizontal rod 66 having one end inserted under an elongated end portion 67 of the lever arm 43 is provided by means of which rod the body 63 is held in its position.

As shown, the knife can be moved to an intermediate position and fixed as by means of ratchet 16. By insertion of a key or the like in the open-

ing and slot at 79, 82, the knife shaft and knife can be rotated, as, for example, if it should be desired to perform a grinding operation.

The mode of operation is in just a few words as follows: After the meat to be sliced is placed on the table 5 and the latter has been advanced by the handle 52 to the position intended for cutting a slice, the operating arm 4 is swung down whereby the knife 2 is brought into rotation and cuts a slice. Upon returning the arm together with the then idle knife, the coupling member 26 on the shaft 10 actuates the coupling member 27 just before the arm arrives at its uppermost position so that the arm 28 is swung upward carrying along the arm 31. The desired extent of the movement of the latter being controlled by means of the adjustment device 58 to 61. The arm 33 on the lever swings downward whereby the roll ratchet 34, 36, 37 carries along the wheel 35 in the direction of the arrow (Figs. 6 and 7) and thus also the shaft 25 so that the table is advanced one step toward the knife path. At the downward swing of the operating arm again, the coupling member 26 releases the coupling member 27 because the latter, on part of its circumference only is provided with shoulders cooperating with the former. The arm 28 falls down partly due to its own gravity, partly due to the action of the spring 38 on the lever arm 33, which latter, at its upward swing, does not carry along the wheel 35 when the roll ratchet is brought out of engagement with the wheel partly under the action of the lever arm 44.

During the repeated procedure the rotation of the wheel 35 and the shaft 25 clockwise cannot take place without special operation due to the braking action of the roll ratchet. If the table is to be returned the handle 52 is turned clockwise, whereby, as already mentioned, the shaft 51 connected with the handle first causes a displacement of the sleeve 49 so as to actuate the lever arms 43 and 45 for the purpose of releasing the blocking engagement of the roll ratchets, after which the shaft carries along the shaft 25 and thus also the table 5.

The embodiment shown is, of course, only chosen as an example and modifications of the same are possible without departing from the scope of the invention.

Having now described my invention, what I claim as new and desire to secure by Letters Patent is:

1. In a slicing machine, a frame, a shaft journaled in the frame, an arm carried at one end of the shaft and adapted for reciprocal movement, a rotary knife journaled on the arm, a table in the frame movable perpendicularly to the path of the knife, a coupling connected to said shaft and adapted to be actuated as the knife is swung from slicing position and to be released as the arm is swung toward slicing position, a second shaft journaled in the frame and extending transversely of the first shaft, a guide member and a carrier for the table mounted for movement on said guide member, means upon the second and transversely arranged shaft engaging with a portion upon said table so that rotation of said second shaft will cause movement of said table on said guide member, a lever connected with the coupling member, and a lever mounted on the transverse shaft, connections between the levers and means adapted to be actuated by the lever on the shaft for turning the shaft in the direction for feeding the table toward the knife path.

2. In a slicing machine, a frame, a shaft jour-

nalled in the frame, an arm carried at one end of the shaft and adapted for reciprocal movement, a rotary knife journalled on the arm, a table in the frame movable perpendicularly to the path of the knife and guide means for the table comprising 5 guide rails for the table adapted to travel on guide bars, said guide bars being journalled in the frame, the end of each guide bar remoted from the knife path being flattened, and the 10 length of the flattened portion of the bars corresponding to the length of said guide rails.

3. In a slicing machine, a frame, a shaft journalled in the frame, an arm carried by the shaft and adapted for reciprocal movement, a rotary 15 knife journalled on the arm, a table movable in the frame perpendicularly to the path of the knife, a coupling connected to the shaft and adapted to be actuated as the arm is swung from slicing position and to be released as the arm is 20 swung toward slicing position, a second shaft journalled in the frame and extending transversely of the first-named shaft, guide means in said frame, a carrier for the table mounted on said 25 guide means, means upon the second shaft engag- 30 ing a portion upon the table so that rotation of said second shaft will cause movement of said table upon said guide means, a lever connected to the coupling member, a two-armed lever pivotally mounted on the second and transversely ar- 35 ranged shaft, one arm of said lever having a shoulder for engaging the lever connected to the coupling, a wheel fixed on the transverse shaft, and coupling devices on the second arm of the two-armed lever, said devices being adapted, as 40 35 the lever on the transverse shaft is moved in one direction, to engage and rotate the wheel on the transverse shaft, and, as the lever is swung in the opposite direction, to cause the wheel to be blocked.

40 4. In a slicing machine, a frame, a shaft journalled in the frame, an arm carried by the shaft and adapted for reciprocal movement, a rotary knife journalled on the arm, a table movable in the frame perpendicularly to the path of the 45 knife, a coupling connected to the shaft, adapted to be actuated as the arm is swung from slicing position and to be released as the arm is swung toward slicing position, a transverse shaft journalled in the frame, a carrier for the table, guide 50 means in said frame supporting said carrier, means upon said transverse shaft engaging a portion upon said table so that rotation of the trans- 55 verse shaft will cause movement of the table, a lever connected to said coupling, a two-armed lever pivotally mounted on the transverse shaft, a shoulder on the latter lever for engaging the coupling lever, a wheel fixed on the transverse shaft, the second arm of the lever on the trans- 60 verse shaft carrying a ratchet head, a roll ratchet mounted in said head, and having a path for the roll tapering upwardly, said ratchet roll being adapted to rotate said wheel in one direction and to block rotation in the opposite direction.

5. A slicing machine comprising a frame, a 65 shaft journalled in the frame, an arm carried by the shaft and adapted for reciprocal movements, a rotary knife journalled on the arm, a table movable in the frame perpendicularly to the path of the knife, a coupling connected to the shaft and 70 adapted to be actuated as the arm is swung from slicing position and to be released as the arm is swung toward slicing position, a second shaft journalled in the frame and extending transversely of the first shaft, a guide and a carrier for the 75 table mounted for movement upon said guide,

means upon said transversely arranged second shaft engaging with a portion upon said table so that rotation of said transverse shaft will cause movement of the table upon said guide, a lever connected to the coupling member, a two-armed lever pivotally mounted on the transverse shaft, one of the arms of the said lever having a shoulder for engaging the lever connected to the coupling, a wheel fixed on the transverse shaft, coupling devices carried by the second arm of the two-armed lever and adapted to engage and rotate the wheel as the lever is moved in one direction and to block rotation of the wheel as the lever is moved in the opposite direction, a rod pivotally mounted in the frame and extending parallel to said transverse shaft, a graduated disc connected to the rod and arranged outside the said frame, means for adjusting the disc, an arm fixed on the rod and extending into the path of the drive means for said wheel, whereby the motion of two-armed lever and the feed of the table can be controlled.

6. In a slicing machine, a frame, a shaft journalled in the frame, an arm carried by the shaft, a rotary knife journalled on the arm, a table 25 movable in the frame perpendicularly to the path of the knife, a rack carried by said table, a coupling connected with the shaft and adapted to be actuated only as the knife arm is swung from slicing position, another shaft journalled in the 30 frame and extending transversely of the first shaft, a toothed wheel journalled on the shaft and meshing with the rack carried by the table, a lever connected with the coupling, a two-armed lever pivotally mounted on the transverse shaft, 35 one arm of said lever engaging the coupling lever, a wheel fixed on the transverse shaft, a ratchet head carried by the other arm of the two-armed lever, said head being provided with a path tapering upwardly and a roller in said path, said roller 40 ratchet being adapted to actuate the wheel and turn it in one direction, a spring in the ratchet head path for pressing the roller upwardly, a second ratchet head arranged at the opposite side of the periphery of the wheel and having a down- 45 wardly tapering path in which a roller is arranged, and means for actuating the rollers for releasing the wheel, whereby the transverse shaft can be turned to move the table from the path of the knife.

7. In a slicing machine, a frame, a shaft journalled in the frame, an arm carried by the shaft, a rotary knife journalled on the arm, a table movable in the frame perpendicularly to the path of the knife, a rack carried by said table, a coupling 55 connected with the shaft and adapted to be actuated only as the knife is swung from slicing position, a hollow shaft journalled in the frame and extending transversely of the first shaft, a toothed wheel on the shaft for engaging the 60 rack carried by the table, a lever connected with the coupling, a two-armed lever pivotally mounted on the transverse shaft, one arm of said lever engaging the coupling lever, a wheel fixed on the trans- 65 verse shaft, a ratchet head carried by the other arm of the two-armed lever, and having an upwardly tapering path in which a roller is carried, a spring in the said path for pressing the roller upwardly, a second ratchet head arranged at the opposite side of the periphery of the wheel 70 and having a downwardly tapering path in which a roller is mounted, said roller ratchets being adapted to engage and rotate the wheel in one direction and block rotation in the opposite direction, a rod in said hollow shaft, connections be- 75

- tween the rod and shaft, means for imparting to the rod a simultaneous peripheral and axial movement in the hollow shaft, a sleeve slidable on the transverse shaft, means for connecting the sleeve to the transverse shaft and the inserted rod, and means actuated by the sleeve as it is displaced for actuating the rolls in the ratchets to release the wheel on the transverse shaft.
8. In a slicing machine, a frame, a shaft journalled in the frame, an arm carried by the shaft, a rotary knife journalled on the arm, a table movable in the frame perpendicularly to the path of the knife, a rack carried by said table, a coupling connected with the shaft and adapted to be actuated only as the knife is swung from slicing position, a hollow shaft journalled in the frame and extending transversely of the first shaft, a toothed wheel loosely mounted on the hollow shaft, and adapted to engage the rack carried by the table, a lever connected to the coupling, a two-armed lever pivotally mounted on the transverse shaft, one arm of said lever engaging the coupling lever, a wheel fixed on the transverse shaft, a ratchet head carried by the other arm of the two-armed lever and having an upwardly tapering path in which a roller is carried, a second ratchet head arranged at the opposite side of the periphery of the wheel and having a downwardly tapering path in which a roller is located, said roller ratchets being adapted to engage and turn the wheel in one direction and to block rotation in the opposite direction, a rod in the hollow shaft, said hollow shaft being provided with a cam groove and an oval opening, and the inserted rod having pins cooperating with the groove and opening, and a sleeve slidable on the hollow shaft, the pin carried by the rod and passing through the oval opening in the shaft being adapted to connect the sleeve to the rod.
9. In a slicing machine, a frame, a shaft journalled in the frame, an arm carried by the shaft, a rotary knife journalled on the arm, a table movable in the frame perpendicularly to the path of the knife, a rack carried by said table, a coupling connected with the shaft and adapted to be actuated only as the knife is swung from slicing position, a hollow shaft journalled in the frame and extending transversely of the first shaft, a toothed wheel on the hollow shaft adapted to engage the rack carried by the table, a lever connected to the coupling and a two-armed lever pivotally mounted on the transverse shaft, one arm of the latter lever engaging the coupling lever, a wheel fixed on the transverse shaft, a ratchet head carried by the other arm of the two-armed lever, and having an upwardly tapering path in which a roller is arranged, a second ratchet head arranged at the opposite side of the periphery of the wheel having a downwardly tapering path in which a roller is located, said roller ratchets being arranged to engage and turn the wheel in one direction and to block its turning in the opposite direction and means for releasing the blocking devices, comprising a rod inserted in the hollow shaft, a sleeve slidable on the shaft, connections between the sleeve and rod, means for imparting simultaneous peripheral and axial movement to the rod, said sleeve being conical and levers, each having an arm carrying a projection extending into the path of the sleeve and the other arm of each lever having a tongue projecting into the path of one of said ratchet heads.

KARL ERIC OLSSON. 55
